UNITED STATES PATENT OFFICE.

STACY B. HASELTINE, OF CHICAGO, ILLINOIS, ASSIGNOR, BY MESNE ASSIGNMENTS, TO
W. H. MINER, INC., A CORPORATION OF DELAWARE.

ANTIFRICTION BEARING.

Application filed January 18, 1924. Serial No. 686,951.

This invention relates to improvements in antifriction bearings.

One of the objects of the invention is to provide a simple, practical and economical roller bearing especially adapted for use as railway car side bearings and wherein is employed an anti-friction roller that is self-centered without the aid of springs or other relatively delicate parts that are likely to get out of order.

More specifically, an object of the invention is to provide an anti-friction roller side bearing for railway cars, having comparatively few parts and including an anti-friction roller and means for guiding and centering the same.

Other objects and advantages of the invention will be more clearly apparent from the description and claims hereinafter following.

In the drawing forming a part of this specification, Figure 1 is a vertical sectional view taken transversely through the ends of the body and truck bolster of a car, showing my improvements in connection therewith. And Figure 2 is a vertical sectional view taken substantially on the line 2-2 of Figure 1.

In said drawing, 10 denotes the under side of the body bolster and 11 the upper side of the opposed truck bolster. The improved bearing is shown as applied to the truck bolster and comprises, broadly, a housing or retaining member A; an anti-friction element proper B; and counterweights C.

The retaining member or housing A is of substantially rectangular outline and has parallel, spaced end walls 13 and side walls 14, said housing also being provided with apertured lugs 20 extending laterally at the lower ends of the vertical walls whereby the housing may be riveted or otherwise suitably secured to the bolster. The side walls 14 are flanged inwardly toward one another at their upper ends, as at 15.

A bearing block 16 is arranged in place in the bottom of the retaining member in any suitable manner as by peening portions 23 of the lower edges of the end walls 13 against the beveled ends 22 of the bearing block. A hardened wear plate 17 may be arranged on the upper surface of the block 16, as shown. The sides of the bearing block 16 have integral lugs or pins 18 projecting outwardly therefrom to points closely adjacent the side

walls 14, these lugs projecting upwardly above the top face of the block 16 at its sides, as shown in Figure 2.

The anti-friction element B comprises a true cylindrical portion adapted to roll back and forth to either side of normal central position on the wear plate 17 and moves between the opposed side edges of the flanges 15 and projects outwardly therebeyond. Thus the anti-friction element is prevented against endwise shifting, by the side flanges 15.

The counterweights C are formed integral with the bearing roller proper and extend outwardly from the ends thereof, one arranged within each of the guideways formed by the side walls and top flanges of the housing. The counterweights have recesses 19 opening downwardly from the bottoms thereof, these recesses extending normally vertically when the roller is in central position and being of a size slightly greater than the diameter of the lugs 18, as shown in Figure 1, so as to normally be out of contact therewith. These counterweights are ex-

tended downwardly below the roller proper and also below the lugs 18 at opposite sides of the latter. In the instance shown, the lugs 18 are made cylindrical and the recesses 19 are correspondingly formed so that their upper portions are semi-circular with tangent faces extending vertically downwardly from the semi-circular portions, the bottom most portions of the recesses 18 being downwardly flared or rounded off, as clearly shown in Figure 1. With this construction, it is evident that bodily shifting of the roller B is prevented except for such slight amount as is permitted due to the working clearances left between the lugs and the edges of the recesses to minimize any tendency of frictional binding in the return of the roller.

In assembling the parts, the roller will first be mounted on the block and these parts then inserted within the housing after which the peening of the section 23 is done, thereby providing a complete assembled unitary structure suitable for shipment and application without danger of the parts becoming displaced or lost. In this connection, it will be observed that the flanges 15 prevent removal of the roller through the top of the housing.

The normal position of the parts is shown by the full lines in Figure 1, in which posi-

tion the bounding walls of the recesses are spaced slightly from the opposed surfaces of the aligned lugs. When the bearing is brought into action by the relative movement between the bolsters, the anti-friction roller will be rolled to the dotted line position shown, assuming that the bolster 10 is moved to the left, and the counterweights will be tilted to the position shown in dotted lines, in which position they are in unstable equilibrium. When the pressure on the bearing is removed, the anti-friction element B will be returned to its normal central position under the influence of gravity, due to the counter-balancing action of the counterweights C, these counterweights slidably engaging the lugs 18 during their returning movement so that the anti-friction member will be centered and normally kept in its centered position by these lugs.

The lugs or pins also serve to prevent bodily shifting of the anti-friction member longitudinally of its bearing surface, so that the anti-friction member is at all times able to travel its full distance under load. The lugs 18 do not take any load whatever and are not supporting lugs but are merely centering lugs to positively prevent any bodily shifting of the anti-friction element B in excess of the relatively slight working clearance allowed between the lugs and cooperating counterweights.

I have herein shown and described what I now consider the preferred manner of carrying out my invention, but the same is merely illustrative and I contemplate all changes and modifications that come within the scope of the claims appended hereto.

I claim:

1. In a slide bearing, the combination with 40 a retaining member; of a bearing plate therein having pins integral therewith at the sides and extending above the bearing surface; a roller adapted to roll back and forth on the plate between said pins; and counterweights integral with said roller at the ends thereof and extending therebelow, each counterweight being slotted upwardly from the bottom to loosely receive its corresponding pin and coact therewith to center the 50 roller as the latter returns to normal position under the counter-balancing influence of the counterweights.

2. In a side bearing, the combination with 55 a retaining member provided with side and end walls, said side walls having overhanging upper end portions; of an anti-friction element of a width to fit between said overhanging portions, said element being provided with counterweight sections of greater 60 width than the distance between said overhanging portions, each of said counterweight sections being provided with an opening normally extending vertically upward, said element being adapted to be inserted through 65 the open bottom of said retainer; a bearing member upon which said element is adapted to move, said bearing member being adapted to close the open bottom of said retainer; and being provided with lugs extending into 70 the openings in said counterweight sections; and means for securing said bearing member in position to maintain the parts of said anti-friction bearing in assembled relation.

In witness that I claim the foregoing I 75 have hereunto subscribed my name this 14th day of January, 1924.

STACY B. HASELTINE.
